DESIGN FOR A TABLE FORK

John Gordon Fenety, New York, N. Y.

Application April 26, 1946, Serial No. 129,004

Term of patent 14 years

(Cl. D54—12)

To all whom it may concern:

Be it known that I, John Gordon Fenety, a citizen of Canada, residing in New York city, in the county of New York and State of New York, have invented a new, original, and ornamental Design for Table Forks, of which the following is a specification, reference being had to the accompanying drawing, forming part thereof.

Fig. 1 is a horizontal plan view of a table fork; Fig. 2 is a horizontal side view thereof; and Fig. 3 is a cross-sectional view on line 3—3 of Fig. 1, showing my new design.

I claim:

The ornamental design for a table fork, substantially as shown.

JOHN GORDON FENETY.
